A. W. HAWKINS

THIRD AND FOURTH POINT SUPPORT FOR BRAKE BEAMS

Filed Feb. 14, 1922

UNITED STATES PATENT OFFICE.

ARTHUR W. HAWKINS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

THIRD AND FOURTH POINT SUPPORT FOR BRAKE BEAMS.

Application filed February 14, 1922. Serial No. 536,541.

To all whom it may concern:

Be it known that I, ARTHUR W. HAWKINS, a citizen of the United States, residing at the city of Chicago, county of Cook, and 5 State of Illinois, have invented a certain new and useful Improvement in Third and Fourth Point Supports for Brake Beams, of which the following is a full, clear, and exact description, such as will enable others skilled 10 in the art to which it appertains to make and use the same, reference being had to the accompanying drawings, forming part of this application, in which—

Figure 1 is a side elevational view of 15 my improved third point support for brake beams.

Figure 1^a is a sectional view on the line a—a of Figure 1.

Figure 2 is a side elevational view showing 20 the position of the parts on a shoe that is worn.

Figure 3 is a detail view of a modified form of support.

Figure 4 is a detail view of another modified form.

Figure 5 is a detail view of my improvement as applied to a fourth point support.

This invention relates to a new and useful improvement in third and fourth point 30 supports for brake beams, the object being to provide a construction which will insure an even wear of the brake shoe when the same is applied and when the brakes are released cause the brake shoes to be tilted so 35 that their upper ends will lie well away from the wheels.

Heretofore, in the use of third and fourth point supports for brake beams, the supporting shoe or chair has been carried by the 40 inner end of the strut, said shoe or chair riding up a yielding inclined track support, or rolling upon a support whereby the inner end of the beam, i. e., the part of the beam whereby the strut supports the tension member, is raised when the brakes are applied.

In my present invention, the track support is made yielding and carries in fixed 50 relation thereto a saddle or roller upon which the inner end of the strut rides, the parts being so designed that when the brakes are applied the inner end of the strut will be slightly depressed, and when the brakes are released the inner end of the strut will 55 be slightly raised so as to tilt the upper end of the shoe away from the wheel. When

used in connection with fourth point supports, the same action occurs, but for fourth point supports separate bridge pieces between the compression and tension members must be provided to co-operate with the saddles. 60

In the drawings, 1 indicates a spring plank of a truck, usually in the form of a channel member, to which is secured a safety bar member 2. On the end of this bar member 65 is a resilient third point support 3 carrying a saddle roller 4, at or near its outer end, upon which rests and rides the inner end of the strut 6 of the brake beam. 7 is the compression member of the beam. 8 is the 70 tension member, 9 the brake bead, 10 the brake shoe, and 11 the brake hanger.

As shown in Figure 1, a new or unworn shoe is illustrated in its released position in full lines, and when the brake is applied 75 the curve of the shoe will fit the periphery of the wheel causing the inner end of the strut to be depressed, as indicated by dotted lines, thereby depressing the saddle roller. When the brakes are released, the saddle 80 roller will be raised lifting the inner end of the strut and causing the brake shoe to be tilted to the full line position shown, wherein its upper end is further away from the wheel than its lower end, a condition which 85 is to be desired in practice.

In Figure 2, I have shown a worn brake shoe in its applied position, in the full line position of which it will be noted that the inner end of the strut is only slightly depressed and when the brakes are released, as 90 shown by dotted lines, the upper end of the shoe will be tilted further away from the wheel than the lower end.

In Figure 3, I have shown a saddle member 12 as being formed integral with the yielding track member; while in Figure 4 I have shown an integral saddle member 13 as being formed on a return or bent portion of the 95 yielding supporting member.

In Figure 5, I have shown a fourth point support in the form of a saddle roller 15 arranged at the end of a yielding supporting member 16, said saddle member co-operating with a bridge piece 17 having one end 105 bent around the tension member and its opposite end riveted to the compression member.

What I claim is:

1. In a brake beam support, a yielding member fixed to a truck portion, and a sad- 110

dle member arranged on the free end of said yielding member and adapted to slidably engage a part of a brake beam.

2. The combination of a brake beam, of 5 hangers therefor, and means for tilting the beams on the hangers, when the brakes are released, whereby the upper edges of the brake shoes are moved away from the wheels in a released position.

10 3. In a brake beam support, a safety bar, a yielding member attached thereto, a saddle member on the end of said yielding member, and a brake beam having a part engaging said saddle member.

15 4. In a brake beam support, the combination of a brake beam, hangers therefor, a

flexible member carried by a part of a truck, and a member mounted on the free end of said flexible member and forming a seat for the inner portion of said brake beam, said flexible member when the brakes are released occupying its normal position, whereby said beam is tilted on its hangers and the upper edges of the brake shoes are positively moved away from the wheels and when the 20 brakes are applied said flexible member is stressed and moved out of its normal position.

In testimony whereof I hereunto affix my signature this 8th day of February, 1922.

ARTHUR W. HAWKINS.
